UNITED STATES PATENT OFFICE.

ANDREW J. McDADe, OF BROOKLYN, NEW YORK.

DESIGN FOR A CALENDAR-FRONT.

2,371.

Specification for Design.

Patented Oct. 5, 1920.

Application filed May 15, 1920. Serial No. 381,757. Term of patent 14 years.

To all whom it may concern:

Be it known that I, ANDREW J. McDADe, a citizen of the United States, and a resident of the city of New York, borough of Brooklyn, in the county of Kings and State of New York, United States of America, have invented a new, original, and ornamental Design for a Calendar-Front.

Reference is to be had to the accompanying drawing in which the figure is a face view of a calendar front embodying my new design.

I claim:

The ornamental design for a calendar front, as shown.

ANDREW J. McDADe.
